AIRPLANE

Richard T. Cella, Rte. 1, Clarksville Road, Trenton, N.J.

Filed Apr. 19, 1961, Ser. No. 64,821

Term of patent 14 years

(Cl. D71—1)

FIG. 1 is a top plan view of the airplane embodying my design showing one wing partly broken away;

FIG. 2 is a side elevation thereof; and

FIG. 3 is a front elevation thereof.

My design for an aircraft having a narrow fuselage provided with a high tail fin with a horizontal stabilizer at the top thereof is characterized by the specific jet engines at the ends of short, rhomboid-shaped wings, which wings merge with the fuselage above the longer wings located near the bottom of the fuselage, all as shown.

I claim:
The ornamental design for an airplane, as shown and described.
